UNITED STATES PATENT OFFICE.

WILLIAM T. HOLDEMAN AND ELBERT T. FORD, OF HAMMOND, INDIANA; SAID HOLDEMAN ASSIGNOR OF ONE-EIGHTH OF HIS RIGHT TO LOUIS M. HEINTZ AND ONE-EIGHTH TO FRED SOMMER, OF HAMMOND, INDIANA.

HOUSING AND ADJUSTMENT FOR INTERLOCKING SWITCHES.

SPECIFICATION forming part of Letters Patent No. 791,622, dated June 6, 1905.

Application filed November 30, 1904. Serial No. 234,888.

To all whom it may concern:

Be it known that we, WILLIAM T. HOLDEMAN and ELBERT T. FORD, citizens of the United States, residing at Hammond, in the county of Lake and State of Indiana, have invented new and useful Improvements in Housings and Adjustments for Interlocking Switches, of which the following is a specification.

10 This invention has for its object to provide a new and improved adjustment for interlocking switches and derails and a housing for same for the purposes of preventing snow and ice and other debris from interfering with the switch and derail adjustment.

15 With this object in view the invention consists of the detail of construction and arrangement, which will more fully appear herein-after.

20 In the accompanying drawings, which form a part of this application, Figure 1 is a perspective view showing our invention in position. Fig. 2 is a transverse-sectional view of the housing and adjustment. Fig. 3 is a sectional view along the line 3 3.

25 Like numerals and letters of reference indicate corresponding parts in the several views.

The letters A A designate the rails of a railroad fastened upon the usual sleepers in the usual manner, and B B designate the switch-rails having the switch-bar 1 connected thereto and the said switch-bar having the interlocking switch-housing C, bolted thereto by means of the bolts 2 3. The said switch-housing is of tubular construction having the ends thereof interiorly threaded and having the flange 4 integrally connected therewith.

D is the movable plug, being exteriorly

threaded and having the bolt-head 5 of the usual construction for operating the said movable plug.

40 The numeral 6 designates the switch-operating rod, and the same operates within the tubular plug 7, the plug 7 being exteriorly threaded and operating within the switch-housing C and is also provided with a bolt-head for operating same. The switch-operating rod 6 is provided with the head 9, which conforms with the tubular interior of the switch-housing C. As can be readily seen, the 45 formation of the interior of said switch-housing permits a lateral "play," and the same can be adjusted by means of the plugs D and C.

50 Having thus described our invention, what we claim as new, and desire to secure by Letters Patent, is—

55 In a housing for interlocking switches and derails, the combination with a tubular housing having the interior ends threaded, an exteriorly-threaded movable plug working in one end of said housing, a switch-operating rod 60 the head thereof operating in same and passing through the exteriorly-threaded tubular plug, the tubular plug operating within said housing 65 and a chamber being formed between the ends of the said plugs, substantially as set forth and described.

65 In testimony whereof we affix our signatures in presence of two subscribing witnesses. 70

WILLIAM T. HOLDEMAN.
ELBERT T. FORD.
